UNITED STATES PATENT OFFICE

2,513,907

LOOM CHECK LINKAGE

Carl H. Bacon, Cleveland, Ohio, assignor to The Weatherhead Company, Cleveland, Ohio, a corporation of Ohio

Application June 11, 1948, Serial No. 32,428

4 Claims. (Cl. 139—161)

1

This invention relates to looms and more specifically to a novel mounting means for the picker stick that casts a shuttle to and fro across the shed. This invention is related to application Serial Number 782,341, filed October 27, 1947 by George H. Hufferd and assigned to The Weatherhead Company.

It is an object of the present invention to mount a picker head so that it positively and accurately traverses a desired path by mounting the picker head upon a set of links, the mounting including a hydraulic check device arranged so that the check device is undisturbed by pivoting of the picker stick. Briefly, this is accomplished by mounting the housing of a hydraulic check device on a bracket carried by the rock shaft. The lower end of the picker stick is guided by link means extending from the picker stick to the check mounting bracket. The upper end of the picker stick is guided by a link extending down from the lay to a midportion of the stick. In this manner, the check rocks with the shaft but is undisturbed by pivoting of the stick, so that the hydraulic fluid in the check is always properly disposed for best operating conditions.

This and other objects and advantages will be apparent to one skilled in the art as the following detailed description of the preferred embodiment of my invention proceeds.

In the drawings:

Fig. 1 represents a side elevation of a preferred embodiment of the invention; and

Fig. 2 is an end view of the assembly.

The loom rock shaft R is mounted for swinging in a loom frame member 10 by means of a bearing 11. The sword S supports the lay portion 12 which provides a track for the shuttle in the conventional manner. It is understood that in looms of this type, a pair of picker sticks are mounted oppositely, only one of such sticks being shown in the figures.

The picker stick P is mounted by a link system to be described in detail presently and is connected to a hydraulic check device C. The exact construction of the check device forms no part of this invention; suitable constructions are disclosed in the copending applications of Roy O. Balogh, Hydraulic Check, Serial No. 670,252, filed May 16, 1946, now Patent No. 2,483,517; Roy O. Balogh, Hydraulic Loom Check, Serial No. 702,953, filed October 12, 1946, now Patent No. 2,506,697 and, George H. Hufferd, Combination Loom Picker Balogh, Hydraulic Check, Serial No. 670,252, filed October 27, 1947. It will suffice to say that the check device checks at the end of the power

2

stroke which is initiated by power strap 14, after which the picker stick returns to the neutral position illustrated in the drawings, to thereupon receive the impact of the shuttle. This impact carries the picker stick to the end of its return stroke with the check device acting to bring the same to a dead stop without rebound.

The check device housing is mounted on the end of the rock shaft by means of support bracket 15 and is retained thereon by set screws as at 16. The body 17 of the check device houses the working pistons, and members 18 are adjustments for controlling the action of the device. It is noted that with this mounting, the adjustments 18 are readily accessible. Arm 20 is pivoted as at 21 to actuate the pistons in the check device in response to motion of the picker stick. Bracket 49, clamped to the stick by screw 41, carries ball member 42 which in turn connects to arm 20 of the check device through part 43.

The mounting bracket of the check device is formed to mount cross-shaft 22, to which is pivoted a pair of links L. The other ends of the link are pivoted as at 23 to a bracket member 25 mounted on the picker stick. Set screws 26 and clamp plate 27 are provided so that the position of bracket 25 on the picker stick is adjustable. With this mounting, the lower end of the picker stick follows a restrained substantially vertical motion within the limits of its operation.

In order to bias the picker stick toward the neutral position after completion of the power stroke, a spring is provided which reacts against plate 28 clamped to the stick. The lower end of the plate is notched as at 29 and a threaded eye bolt 30 carries adjusting nut 31 which rests in the notch. Spring 32 connects with eye bolt 30 in the picker stick and with a fixed eye bolt 33. The action of spring 32 is described in detail in the copending application of George H. Hufferd, Serial No. 782,341, mentioned above.

To complete the mounting of the picker stick, an upper link or arm A is provided. The lower end of the arm is pivoted to ball 52 on bracket 50, adjustably clamped to the stick by set screws 51. The construction and operation of ball joints such as those illustrated, is known to all those skilled in the art and accordingly is not elaborated upon.

The upper end of arm A is pivoted to a similar ball member 54 on the upper bracket 55. The bracket is adjustably mounted on a lay portion 12 by means of bolts 58 which extend through slots 57 formed in the fixed mounting plate 56.

The picker head 60 has a pocket 61 for reception of the shuttle.

The line $x-x$ represents a straight line parallel to the lay which line is substantially the path traversed by the picker with certain exceptions, the reasons for the exceptions and the advantages thereof being explained in detail in the aforesaid application of Hufford, Serial No. 782,341.

It can be seen that I have provided a novel combination of a linkage-mounted picker stick and a hydraulic check device which is simple; the check device is accessible, and relatively undisturbed by operation of the loom. Various modifications in the preferred embodiment described may be made without departing from the essence of the invention, and, accordingly, I contemplate that the appended claims and not the illustrated embodiment are determinative of the scope of my invention.

What is claimed is:

1. In a loom, a frame having a rock-shaft bearing, a rock shaft pivoted in said bearing, a lay assembly, a picker stick and a picker, linkage means to mount the picker stick on said assembly so that the picker moves substantially in a straight line, a hydraulic check device having a housing element rigidly supported by said rock shaft on the outboard side of said bearing and a piston element pivotally connected to said picker stick, linkage mounting bracket means on said rockshaft outboard of said bearing, said linkage means comprising a first link pivoted to said assembly and to said picker stick, and a second link pivoted to a lower end portion of the picker stick at one end and to said mounting bracket means carried by said rock shaft at the other end, said check housing element overlying a substantial extent of said second link.

2. In a loom, a frame, rock shaft, and lay assembly, a picker stick and a picker carried thereby, linkage means to mount the picker stick on the loom so that the picker moves substantially in a straight line, a hydraulic check device including a housing element and mounting bracket therefor rigidly supported by said rock shaft and a piston element pivotally connected to said picker stick, said linkage means comprising a first link pivoted to said lay assembly and to said

picker stick, and a second link pivoted to a lower end portion of the picker stick and to said mounting bracket.

3. In a loom, a frame, rock shaft, and lay assembly, a picker stick and a picker carried thereby, linkage means to mount the picker stick on the loom so that the picker moves substantially in a straight line, a hydraulic check device including a housing element and mounting bracket therefor rigidly supported by said rock shaft and a piston element pivotally connected to said picker stick, said linkage means comprising a first link pivoted to said lay assembly and to a midportion of said picker stick, and a second generally horizontal link pivoted to a lower end portion of the picker stick and to said mounting bracket.

4. In a loom, a frame including a rock shaft bearing, a rock shaft, and a lay assembly, a picker stick including a picker, linkage means to mount the picker stick on the loom so that the picker moves substantially in a straight line, a hydraulic check device including a housing element and mounting bracket therefor rigidly supported by said rock shaft outboard of said frame bearing and a piston element pivotally connected to said picker stick, said linkage means comprising a first link pivoted to said lay assembly and to said picker stick, and a second link pivoted to a lower end portion of the picker stick and to said mounting bracket.

Certificate of Correction

Patent No. 2,513,907

July 4, 1950

CARL H. BACON

It is hereby certified that errors appear in the printed specification of the above numbered patent requiring correction as follows:

Column 1, line 53, strike out the words "Balogh, Hydraulic Check, Serial No. 670,252" and insert instead *Staff Linkage and Check, Serial No. 782,341*;

and that the said Letters Patent should be read with these corrections therein that the same may conform to the record of the case in the Patent Office.

Signed and sealed this 26th day of September, A. D. 1950.
